UNITED STATES PATENT OFFICE.

PETER BARRY, OF NEW YORK, N. Y.

RETICULATED WORK FOR CARRIAGE-BODIES, &c.

SPECIFICATION forming part of Letters Patent No. 259,461, dated June 13, 1852.

Application filed January 28, 1852. (Specimens.)

To all whom it may concern:

Be it known that I, PETER BARRY, of the city of New York, in the county and State of New York, have invented certain new and useful Improvements in Reticulated Work for Carriage-Bodies and for other Purposes, of which the following is a specification.

My invention relates especially to imitations of cane-work and wicker-work to be employed 10 on wagon-bodies and other carriage-bodies to give them the appearance of being covered with a fabric of cane or wicker; but the invention is also applicable for the covering of other articles. The desired effect has been produced 15 by applying perforated leather or perforated cloth, thickly covered with paint, to the carriage-body, and also by painting; but the first method is objectionable because the perforated leather or cloth is very hard to fit properly to 20 sloping and curved bodies, and the second method is objectionable because the painting must be gone over and allowed to dry a great many times to give the cane or wicker imitation the degree of projection or relief desired.

25 My invention consists in an imitation of cane, wicker, or other woven or net work, produced by a reticulated or perforated fabric or tissue made of thick oil-paint or other composition of a similar nature, and adapted to be applied 30 to the carriage-body or other article by means of such varnishes as are usually employed for varnishing such bodies or articles, and for the securing thereto of other imitation cane fabrics.

In making this imitation of cane or wicker 35 or other woven or net work, which may be considered a new article of manufacture, I employ a mold grooved or intagliated to form the desired pattern; and my invention also consists in the method whereby the imitation cane, 40 wicker, or other woven or net work is made of oil-paint or other composition of similar nature insoluble in water, said method consisting in first coating the mold with an adhesive substance soluble in water, then covering the 45 mold with the composition, and pressing it into the grooved or intagliated portions thereof and allowing the composition to dry, then sandpapering off or otherwise removing all the composition except that contained in the grooved 50 or intagliated portions of the mold, and finally dissolving by water the adhesive substance

which secures the composition to the mold, and thereby freeing the fabric or tissue from the mold.

In the accompanying drawings, Figure 1 represents a small piece of the improved fabric or tissue. Fig. 2 represents a face view of a portion of the mold employed to make the same. Fig. 3 represents a transverse section of the mold filled with composition. Fig. 4 represents on a small scale a portion of a wagon-body having the imitation cane applied thereto, and Fig. 5 is a diagram showing the shape of fabric or tissue required to cover said wagon-body.

65 Similar letters of reference designate corresponding parts in all the figures.

Referring first to Figs. 1, 2, and 3, A designates a piece of the fabric or tissue, and B designates the mold employed for making the 70 same. The mold may be made of wood or other suitable material, and the composition which I have found to be desirable for the purpose is composed of the same materials as ordinary oil-paint, but may have additional 75 white lead or other suitable substance added to give it more body. Any suitable compound or composition insoluble in water may, however, be employed for the purpose. The mold B is engraved or grooved on the surface, as clearly 80 shown in Fig. 2, to form the desired pattern of fabric or tissue, and before it is used I prefer to coat its face with shellac varnish or other varnish or substance impervious to water. The 85 mold having been first coated with an adhesive substance or material which is soluble in water—such, for instance, as an aqueous solution of gelatine or gum-arabic—the face of the mold is covered with the paint or composition, which may be poured on the mold and spread by 90 means of a brush or other implement, and made to fill all parts of the mold. The composition is then allowed to dry, and is retained on the mold by the adhesive substance. After drying, 95 all the composition which covers the face of the mold and is not contained in the grooves or intaglio of the mold is removed by sandpapering it over or in any other suitable manner, leaving a reticulated or perforated fabric or tissue, which may be released from the mold by immersing the latter in water, and thereby dissolving the gum, gelatine, or other adhesive 100

substance which was applied before the composition. The fabric or tissue is then applied to the carriage-body with the varnish ordinarily employed for carriage-work, and may be 5 varnished over as many times as desirable.

Referring now to the diagrams Figs. 4 and 5, C designates a portion of a carriage or wagon body, having a curved and beveled or sloping surface, to which the reticulated fabric or 10 tissue is applied, and D designates the piece of the fabric or tissue which is of the shape required for the purpose. It will be readily seen that a straight piece of fabric or tissue would not be suitable because of the slope or bevel 15 of the body, and that the fabric or tissue must be curved, as shown in Fig. 5.

As the molds which I employ are of wood, they may be made of any shape to produce a piece of fabric or tissue of the desired outline 20 at a small expense, while to perforate a piece of leather or muslin of such curved or irregular shape would be very expensive.

The pattern of the reticulated work may be varied to imitate any kind of weaving, interlacing, or netting of threads, withes, or rings. 25

What I claim as my invention, and desire to secure by Letters Patent, is—

1. As a new article of manufacture, an imitation of cane, wicker, or other woven or net work for carriage-bodies or for other purposes, 30 consisting of a reticulated fabric or tissue of oil-paint or other analogous composition, substantially as and for the purpose herein described.

2. The method of making imitation cane-work fabric or tissue, consisting in first coating a mold with an adhesive substance soluble in water, then covering and filling the mold with a composition of which the fabric or tissue is to be made, and allowing such composition to dry, then sandpapering off or otherwise removing all the composition except that contained in the grooved or intagliated portions of the mold, and finally dissolving the adhesive substance by immersing the mold in water, and thereby releasing the reticulated fabric or tissue therefrom, substantially as and for the purpose herein described. 40 45

PETER BARRY.
